UNITED STATES PATENT OFFICE.

ANTONE CONSTANTIN, OF NEW YORK, N. Y.

INSECTICIDE.

1,390,088.

Specification of Letters Patent. Patented Sept. 6, 1921.

No Drawing.

Application filed March 26, 1920. Serial No. 369,073.

To all whom it may concern:

Be it known that I, ANTONE CONSTANTIN, a citizen of the United States, and a resident of the city of New York, borough of Manhattan, county and State of New York, have invented a new and Improved Insecticide, of which the following is a full, clear, and exact description.

This invention relates to insecticides, and has for an object the provision of an insecticide which is highly poisonous to insects, and when placed in an infected region will remain in place for long periods of time without being blown away.

My improved insecticide is especially valuable in the extermination of bed bugs and other house pests. There are many compositions for a similar purpose sold commercially, but most of these are in a powdered form and when sprinkled around in a room or house which is infected, the dust is carried around by the air and due to its highly poisonous character, is often detrimental to the health of human beings. In my improved insecticide, I provide a vehicle which will give the resulting composition a salve like character, so that when spread upon a surface, it will firmly hold the poisonous ingredients and prevent them from entering the air which is breathed in by the occupants of the house.

I have discovered that green paint powder and yellow paint powder both have very poisonous properties toward bed bugs and other house pests. Yellow paint powder consists primarily of chromate of lead having the formula $PbCrO_4$, and the green paint powder is a mixture of chromate of lead, Prussian blue called ferric ferrocyanid, and having the formula $Fe_4(Fe(CN)_6)_3$, and barytes. These are generally mixed in the following proportions: chromate of lead,

20%; ferric ferrocyanid, 5%, and barytes, 75%. It is a well known fact that most lead salts are highly poisonous to insects, and lead chromate is especially so since it is combined with the chromate ion which is also poisonous. Thus the lead chromate is combined with the Prussian blue which is also poisonous to insects. I have found that my composition works best with ingredients in the following proportions by weight:

Lard	8 parts	
Soap	1 part	55
Yellow paint powder	1 part	
Green paint powder	1 part	

The lard and the soap act as a vehicle which gives the final composition a salve like character, and also serve to attract the insects to the composition upon which they feed. Any other suitable ingredients may be used which will accomplish the same result, and furthermore, the proportions in my composition can be varied considerably with more or less successful results. The ingredients are mixed thoroughly together in any order, preferably with the aid of heat.

I would state in conclusion that while the example described constitutes a practical embodiment of my invention, I do not limit myself strictly to the aforementioned details since manifestly the same can be considerably varied without departure from the spirit of the invention as defined in the appended claim.

Having thus described my invention, I claim as new and desire to secure by Letters Patent:

An insecticide, containing lard, soap, chromate of lead, ferric ferrocyanid, and barytes in about the proportions specified.

ANTONE CONSTANTIN.
